WEB CUTTING AND SCORING DEVICE

Filed April 7, 1933

UNITED STATES PATENT OFFICE

1,998,357

WEB CUTTING AND SCORING DEVICE

Martin Carlson, Chicago, Ill.

Application April 7, 1933, Serial No. 664,988

2 Claims. (Cl. 164—39)

This invention relates to certain novel improvements in web cutting and scoring devices, and has for its principal object the provision of an improved construction of this character which 5 will be highly efficient in use and economical in manufacture.

Another object of this invention is to provide a novel and improved device for cutting a moving web, such for example, as a web of paper or fabricated material, longitudinally into strips.

Still another object of the invention is to provide a novel and improved device for forming score lines, fold lines, or lines of weakened union in a moving sheet or web, such for example, as a 15 web of paper or fabricated material.

A further object of the invention is to provide a device for cutting a moving web of abrasive material, such, for example, as sandpaper, longitudinally into strips.

Another object of the invention is to provide a device for forming score lines in a moving web of abrasive material, such, for example, as sandpaper.

Other objects will appear hereinafter.

The invention consists in the novel combination and arrangement of parts to be hereinafter described and claimed.

The invention will be best understood by reference to the accompanying drawing, showing 30 the preferred form of construction and in which:

Fig. 1 is a perspective view of a preferred form of the invention;

Fig. 2 is a vertical sectional view of the same;

Fig. 3 is a view on line 3—3 in Fig. 2, partly in 35 section and partly in rear elevation;

Fig. 4 is a sectional view on line 4—4 in Fig. 2;

Fig. 5 is a sectional view on line 5—5 in Fig. 2;

Fig. 6 is a perspective view of one of the scoring knives embodied in the invention; and

Fig. 7 is a perspective view of one of the cutting knives embodied in the invention.

The new device is indicated generally at 10 in the drawing and includes a support or frame 11 having spaced uprights 12. Having trunnions 45 13 journaled in the frame uprights 12 are guide rollers 14 between which a web 15 of abrasive sheet material such as, for example, sandpaper, emery cloth or the like, is driven by web-advancing rollers 16. The rollers 16 may be operated by 50 any suitable means (not shown).

Spaced forwardly of the guide rollers 14 and also having trunnions 17, journaled in the frame uprights 12 is a roller 18; the roller 18 being spaced forwardly of the guide rollers 14, in 55 the frame 10, relative to the direction of travel

of the web 15, which is from right to left in Figs. 1 and 2.

Better to guide the web 15 between the rollers 14, and to prevent lateral shifting of the web 15, a pair of guiding flanges 19 are provided. These flanges 19 are L-shaped in cross section and each has an arm extended above and spaced from a strip 20. The flanges 19 cooperate with the strips 20 to provide guide slots 21 (Figs. 2 and 3) for conducting the web 15 therethrough.

The strips 20 and flanges 19 are mounted on blocks 22 which are slidably mounted on the frame 10 for adjustment relative to each other axially of the rollers 14. This adjustment is effected by bolts 23 which carry the blocks 22 and 15 are slidable in a slot 24 formed between spaced strips 25. These strips 25 are mounted on the frame 10 and extend axially of the rollers 14. To clamp the blocks 22, strips 20, and flanges 19 in an adjusted position and in spaced relationship 20 relative to each other wing nuts 26 are provided on the bolts 23.

Arranged at spaced intervals transversely across the frame 10 between the uprights 12, and axially of the rollers 14 and 18, is a series of 25 cutter knives 27 each having a shank 28 and a cutting edge 29. These cutting knives 27 are adjustably mounted on a supporting bar 30 which extends between and has its end portions mounted in the uprights 12. This supporting bar 30 30 is clamped in position by set screws 31 mounted in the uprights 12.

The cutter knives 27 are held in position and in spaced relation on the supporting bar 30 by means of clamping members 32 (Fig. 4). Each 35 of these clamping members 32 has an aperture 33 formed therein for the passage of the bar 30 and each clamping member 32 has a slot 34 formed therein through which the shank of a knife is extended. Each clamping member 32 40 includes a set screw 35 that bears on the corresponding knife shank.

The knives 27 are adjusted in the clamping members 32 so that their knife edges 29 bear upon the web 15 as the same passes over the 45 roller 18 and thus sever the web 15 longitudinally into strips.

It is frequently desirable to score the strips cut from the abrasive web 15 so that the strips may be pulled longitudinally by a mechanic 50 whereby the folded edge may be inserted into, and used to sandpaper, a place that is not accessible to the flat face of the strip. To accomplish this end I may arrange at spaced intervals between the uprights 12 scoring knives 39 each hav-

ing a shank 40 and a rotary scoring blade 41 carried thereby. The shanks 40 of these scoring knives 39 are mounted, as are the cutter knives 27 in clamping members 32 so that the rotary blades 41 bear upon the web 15 above the roller 18.

To prevent vibration and lateral shifting of the cutter knives 27 and of the scoring blades 41 during the cutting and scoring operations, I 10 mount on the support 10 a supporting bar 36 that extends parallel to the bar 30 above the roller 18. The end portions of the bar 36 are releasably mounted in slotted clamping blocks 37 that are attached to the inner sides of the uprights 12. 15 On the bar 36 are arranged stabilizer members 37 each having a slot 38 formed in its lower side for the reception of the shank 28 of a cutter knife 27 or for the reception of the shank 40 of a scoring knife 39. Each of these stabilizer members 20 37 includes a set screw 42 which bears upon and clamps the stabilizer to the supporting bar 36. These stabilizer members 32 cooperate with the supporting bar 36 to prevent lateral shifting of the cutting knives 27 and scoring knives 39 during 25 the cutting and scoring operations, and thus function to keep the blades 29 of the cutter knives and the blades 41 of the scoring knives 39 in their tracks 44 and 43, respectively; thus assuring uniformity in the widths of the strips 30 cut from the web and in the distances between the score lines 43.

In the drawing both cutter knives 27 and scoring knives 39 are shown assembled together on the supporting bar 30. However, it is to be understood that the scoring knives 39 are not essential to the operation and function of the cutter knives 27 and vice versa. Hence, the device may be assembled with only cutter knives 27 on the supporting bar 30 should it be desired to cut 35 the web 15 into strips but not to score the same. Conversely, the device may be assembled with only scoring knives 39 on the supporting bar 30 should it be desired to form score lines 43 in the web 15 but not to cut the web into strips.

45 The device may be used for cutting or scoring

a moving web of any kind of sheet material and is not limited in use to cutting or scoring abrasive materials. Thus the device may be used for cutting and scoring webs of paper, fabric, and the like.

5 While I have illustrated and described the preferred form of construction for carrying my invention into effect, this is capable of variation and modification, without departing from the spirit of the invention. I, therefore, do not wish 10 to be limited to the precise details of construction set forth, but desire to avail myself of such variations and modifications as come within the scope of the appended claims.

Having thus described my invention what I 15 claim as new and desire to protect by Letters Patent is:

1. In a web cutting and scoring device, a frame, a supporting bar carried by the frame, a cutting knife having a shank, a fastening block 20 having an opening for slidably receiving said supporting bar and an opening for slidably receiving said shank, said shank being arranged in contact with said bar, and a screw having threaded relation with said block and arranged in 25 operative relation with the shank and the bar for pressing the two together, to clamp the shank and lock the block in position upon the bar.

2. In a web cutting and scoring device, a frame, a supporting bar carried by the frame, a cutting 30 knife having a shank, a fastening block having an opening for slidably receiving said supporting bar and an opening for slidably receiving said shank, said shank being arranged in contact with said bar, and a screw having threaded relation with said block and arranged in operative relation with the shank and the bar for pressing the two together, to clamp the shank in position upon the bar, a second supporting bar fastened to said 35 frame, and a stabilizing block adjustably mounted upon said second supporting bar and having a bifurcated extension arranged for connection with said shank.

MARTIN CARLSON.
